UNITED STATES PATENT OFFICE.

OLIVER KAMM, OF URBANA, AND ERNEST H. VOLLWEILER, OF CHICAGO, ILLINOIS,
ASSIGNORS TO THE ABBOTT LABORATORIES, OF CHICAGO, ILLINOIS, A CORPOR-
ATION OF ILLINOIS.

DI (NORMAL) BUTYL BARBITURIC ACID.

1,331,712.

Specification of Letters Patent. Patented Feb. 24, 1920.

No Drawing.

Application filed January 23, 1919. Serial No. 272,625.

To all whom it may concern:
Be it known that we, OLIVER KAMM, a citizen of the United States, residing at Urbana, in the county of Champaign and State of Illinois, and ERNEST H. VOLLWEILER, a citizen of the United States, residing at Chicago, in the county of Cook and State of Illinois, have invented certain new and useful Improvements in Di (Normal) Butyl Barbituric Acid, of which the following is a specification.

Our invention relates to the synthesis of the di-normal butyl derivative of barbituric acid, a compound possessing the structure,

15

20

and which exhibits pronounced sedative properties and yet possesses a very low toxicity. It was synthesized as is illustrated by the following example:

Illustration:

40 grams of sodium are dissolved in 1 liter of absolute alcohol and 157 grams of di-normal butyl malonic ester (prepared by the action of n-butyl bromid upon malonic ester

in the presence of two moles of sodium ethylate) and 50 grams of urea added. The mixture is heated in an enameled autoclave during six hours at a temperature of 100 to 110° C. After the alcohol is distilled from the reaction mixture, water is added and the di-n-butyl barbituric acid precipitated by acidification with hydrochloric acid. The yield of crude product was 130 grams. It crystallizes from hot water in the form 40 of white needles which melt at 158° C.

We claim:

1. Di (normal) butyl barbituric acid.
2. As a new article of manufacture, the di-normal-butyl derivative of barbituric acid, 45 possessing the structure

which is a white crystalline solid melting at 158° C., and which possesses marked hyp- 55 notic properties combined with a low toxicity.

January 14, 1919.

OLIVER KAMM.
ERNEST H. VOLLWEILER.
